DOOR CHECK

Samuel T. Alexander, Los Angeles, Calif., assignor or one-third to Paul Eddy Richardson, Los Angeles, Calif.

Application November 18, 1941, Serial No. 419,559

6 Claims. (Cl. 16—59)

This invention relates generally to door checks and door return devices.

It is a primary object of my invention to provide a simple device of relatively few parts which may be mounted on a door frame and attached to a door to act as a door check and door return means. It is also an object to provide a simple device of the type indicated which may be used in various places where a yieldable braking and return action is required.

It is a further object of my invention to provide a door check embodying a piston and cylinder in which a rod is provided extending externally of the housing and attached at its inner end to the piston mounted in a plane above the liquid level in the housing so that no positive liquid seal is necessary in the region where the rod passes through the end of the housing.

It is also an object to provide a device of the type indicated embodying a piston and rod in which means are provided for wiping the rod internally of the housing and in addition means in the nature of a baffle are provided for preventing any sudden surge of liquid in the housing from escaping through the opening in the end of the housing through which the rod passes.

It is a further object to provide within a single housing, means for checking the retraction of the door or piston rod, means for yieldably holding the rod in a retracted position and for returning it to such position and catch means for holding the rod in an extended position.

In addition it is an object to provide means for sealing the opening through which the rod passes through the housing when the rod is held in retracted position.

These and other objects will be apparent from the drawing and the following description thereof. Referring to the drawing, which is for illustrative purposes only:

Fig. 1 is a longitudinal central section through a door check and return device embodying the invention;

Fig. 2 is an enlarged cross section on line 2—2 of Fig. 1;

Fig. 3 is an enlarged fragmentary section in the plane of Fig. 1 of one end of the device; and

Fig. 4 is an enlarged cross section on line 4—4 of Fig. 1.

More particularly describing the invention, reference numeral 11 generally indicates an elongate housing. This housing comprises a tubular member 12 of the cross sectional shape indicated in Figs. 2 and 4. Fitted into the ends of this member are end housing members 14—15 respectively. The part 12 may be joined to the parts 14—15 in any suitable way as by sweating the ends of the member 12 around the end elements. The end housing member 14 is provided with an apertured extension 16 so that this end of

the housing may be pivotally mounted on a door frame or the like as generally indicated at 17.

Mounted in the lower portion of the outer housing is a cylinder 18, the ends of which are positioned in annular recesses 14' and 15' of the respective end members. This cylinder is provided with an elongate slot 19 extending a considerable distance along the top of the cylinder from the end 15 as shown. The end of the cylinder opposite to the slotted portion is sealed off from communication with the interior of the housing 11 except through the restricted passageway 20—21 provided in the end housing 14. The passageway portion 21 extends diagonally from the main part and terminates to one side of the cylinder as shown in Fig. 2. This passageway 20—21 is controlled by means of an adjustment screw 22 which can be threadably mounted in the housing element.

20 A hollow piston 24 is slidably mounted in the cylinder 18. This piston is provided at one end with a check valve 25 which cooperates with the valve seat 26 and is retained by the pin 27. The check valve serves to prevent flow of liquid through the piston when it is moved in a direction toward the end member 14. The opposite end of the piston is provided with a crosshead or rigid coupling element 28 which, as shown in Fig. 2, consists of a double strap expanded at its lower end 29 to follow the contour of the inner surface of the piston. The piston is slotted at 30 to accommodate the crosshead, the lower end 29 of which can be secured to the piston by any suitable means. At its upper end the strap encircles a rod 32 which is securely mounted therein in any suitable manner. This door or piston rod extends parallel to the piston but is located above the normal liquid level in the housing 11 which is indicated at 33. The rod passes through an opening 34 in the end member 15 and is provided at its outer end with a suitable fitting 35 as may be desired for pivotally securing the same to a door or the like. The opening 34 is preferably made sufficiently larger than the diameter of the rod to permit of the rod being received without contact with the sides of the opening. This construction serves to prevent any wiping action which might tend to cause liquid to gather on the outside of the housing and at the same time 45 prevents escape of liquid by capillary attraction.

In order to yieldably retain the piston and rod in the retracted position shown, a spring means generally indicated by numeral 36 is provided. One end of this spring means is connected to the housing by means of the apertured lug 37 and the other end secured to the cross head 28 in the hole 28'. Although various types of tension springs might be employed, it is desirable to provide a special spring means in order to achieve 55 the desired force and flexibility within the rela-

tively short movement permitted by the housing and to achieve this inner and outer telescoping springs indicated respectively by the numerals 38 and 39 are provided. Between the springs is a tube 40 and the springs have their inner ends mounted in opposite ends of this tube, namely, the outer spring 39 is secured within the turned end 41 of the tube while the opposite end of the other spring is secured within the turned end 42 of the tube. It is obvious with this construction that when the rod and piston are moved from their retracted position both of the springs are placed under tension.

Preferably a catch means is provided for engaging the member 28 when the rod and piston are in extended position and in the form of the invention shown, this means consists of the clamp 43 provided with the spaced spring jaws 44 adapted to engage the crosshead. The clamp is secured to the end housing element 15 by means of rivets 45 which also serve to hold a combined wiper and baffle means generally indicated by numeral 46.

The combined wiper and baffle means comprises a plate like member 47 which is secured to the end member 15 at its lower end and which extends outwardly therefrom as indicated. Preferably this member closely fits the inner wall of the housing so that any sudden surge of liquid within the housing above its normal liquid level and against the baffle will be prevented from reaching the opening 34 where it could escape to the exterior of the housing. The member 47 is provided with an opening 48 for accommodating a flexible wiper element 49 which can be formed of any suitable material which would not be injured by the particular liquid used in the device.

It may be pointed out that the combined wiper and baffle means is not designed to act as an absolute fluid tight seal between the rod 32 and the housing to prevent escape of liquid. A perfect seal is unnecessary in the construction shown where it is a feature of the invention that the rod 32 is located above the normal level of the liquid in the housing. However, there may be times in the operation of the device when some means are necessary to prevent escape of liquid through the opening 34 as, for example, when there might be a sudden surge of liquid in the housing toward the end 15 as might be caused by a sudden opening of the door to which the device is attached. At such times the combined wiper and baffle means will serve to prevent liquid from splashing out through the opening. At the same time the wiper serves to remove any liquid which may accumulate on the rod and thereby prevent its escape to the exterior of the housing.

Since the wiper 49 may incidentally remove some moisture from the rod 32 as it returns to its normal retracted position it is desirable to provide some means of returning to the main part of the housing any liquid which may accumulate between the baffle and the end housing element. A narrow passageway or channel of very limited capacity indicated at 50 in Fig. 3 serves this purpose without permitting escape of liquid through the opening 34 at such times as there might be a sudden surge of liquid in the housing.

It may be pointed out, however, that in the normal operation of the device there should be little if any tendency for the liquid in the housing to approach the region of the opening 34. The reason for this is that the housing need only

be supplied with liquid to the level shown. Thus, in the operation of the device by reason of the fact that the piston is hollow and the cylinder is provided with a longitudinal slot 19 only a limited amount of liquid rises through the slot 19 as the piston moves from the position in which it is shown to the opposite end of the cylinder, the major portion of the liquid merely escaping through the piston itself.

Although the device is adapted to be installed in a horizontal position there are times when it will not occupy such a position as, for example, prior to the time it is actually installed and possibly at other times such as during installation or at some time when the device may be removed from the door. In order to prevent the escape of liquid from the housing during such times as the device is not arranged in the horizontal position shown in the drawing a seal member 52 is provided on the rod exteriorly of the housing. This seal member is placed just inwardly of the fitting 35 and is adapted to be forced into pressure engagement with the end member 15 in the region of the rod opening 34 by the action of the spring means when the rod and piston are in the retracted position shown. Thus an effective seal is provided to prevent escape of liquid from the housing when the device is not installed for use on a door.

Although the invention has been particularly shown and described, it is contemplated that various changes and modifications may be made and it is intended to cover such changes and modifications as come within the scope of the claims.

I claim as my invention:

1. In a door check and return device, an elongated housing adapted to be pivotally secured to a door frame or the like and extend in a horizontal position; a cylinder in the lower portion of said housing; liquid in said housing filling said cylinder leaving the upper portion of said housing free of liquid; means providing a restricted fluid passageway from one end of the cylinder, the other end of said cylinder being in open communication with the interior of the housing; a piston in said cylinder; a crosshead mounted on one end of the piston and extending upwardly therefrom, a rod mounted at the upper end of said crosshead and extending parallel to the cylinder in a plane above the cylinder and above the level of the liquid in the housing, said rod extending through the end of said housing opposite to that to which the housing is attached to the frame, said rod being provided with means at its outer end for attachment to a door or the like; means in said housing for yieldably holding said piston and rod in a retracted position; and a resilient seal member mounted on said rod exteriorly of said housing and adapted to be forced into pressure engagement with the end of the housing by said yieldable means when the rod and piston are in a retracted position.

2. In a door check and return device, an elongated housing adapted to be pivotally secured to a door frame or the like and extend in a horizontal position; a cylinder in the lower portion of said housing; liquid in said housing filling said cylinder leaving the upper portion of said housing free of liquid; means providing a restricted fluid passageway from one end of the cylinder, the other end of said cylinder being in open communication with the interior of the housing; a piston in said cylinder; a crosshead mounted on one end of the piston and extending upwardly

therefrom, a rod mounted at the upper end of said crosshead and extending parallel to the cylinder in a plane above the cylinder and above the level of the liquid in the housing, said rod extending through the end of said housing opposite to that to which the housing is attached to the frame, said rod being provided with means at its outer end for attachment to a door or the like; means in said housing for yieldably holding said piston and rod in a retracted position; and a combined wiper and baffle in said housing adjacent the end where the rod passes through the housing, said wiper portion being formed of suitable flexible material apertured to receive the rod and said baffle portion being positioned in close proximity to the inner surface of the housing above said cylinder whereby a sudden surge of liquid against said baffle will be prevented from passing the same.

3. In a door check and return device, an elongated housing adapted to be secured to a door frame or the like and extend in a horizontal position; a cylinder in the lower portion of said housing; liquid in said housing covering said cylinder leaving the upper portion of said housing free of liquid; means providing a restricted fluid passageway from one end of the cylinder, the other end of said cylinder being in open communication with the interior of the housing; a piston in said cylinder; a crosshead mounted on one end of the piston and extending upwardly therefrom, a rod mounted at the upper end of said crosshead and extending parallel to the cylinder in a plane above the cylinder and above the level of the liquid in the housing, said rod extending through the end of said housing opposite to that to which the housing is attached to the frame, said rod being provided with means at its outer end for attachment to a door or the like; means in said housing for yieldably holding said piston and rod in a retracted position; and catch means for engagement with said crosshead when said rod and piston are extended for yieldably holding said parts in the extended position.

4. In a door check and return device, an elongated housing having means at one end thereof for pivotally mounting the housing on a door frame or the like in a substantially horizontal position; a cylinder in the lower portion of said housing, said cylinder being provided with a slot extending from the end of said housing opposite to the end which is adapted to be attached to the door frame or the like a considerable distance inwardly therefrom; a hollow piston in said cylinder, said piston being provided with a check valve adapted to prevent flow of liquid therethrough when said piston is moved toward the end of said housing which is adapted to be attached to the door frame or the like; said housing being provided with means forming a restricted fluid passage from the end of said cylinder opposite to the slotted portion to the interior of said housing; said housing being adapted to be provided with a suitable liquid to fill said cylinder and leave the upper portion of the housing free of liquid; a crosshead mounted on the piston and extending upwardly into the upper portion of the housing above the level of liquid; a rod having its inner end mounted in said crosshead and extending substantially parallel to said cylinder above the same in the upper portion of the housing above the liquid level and through the end of said housing opposite to the end adapted to be attached to the frame, the outer end of said rod being

adapted to be attached to a door or the like; spring means in said housing for yieldably holding said rod and piston in a retracted position; a combined wiper and baffle means mounted at the end of said housing through which the rod passes, the wiper portion being apertured to receive the rod and the baffle portion being adapted to closely fit the inner wall of the housing in a region inwardly of the point at which the rod passes through the end of the housing; and a seal member mounted on said rod exteriorly of the housing and adapted to be forced into pressure engagement with the end of the housing by said spring means.

5. In a door check and return device, an elongated housing adapted to be secured to a door frame or the like and extend in a horizontal position; a cylinder in the lower portion of said housing; means providing a restricted fluid passageway from one end of the cylinder, the other end of said cylinder being in open communication with the interior of the housing; a piston in said cylinder; a cross-head mounted on one end of the piston and extending upwardly therefrom, a rod mounted at the upper end of said crosshead and extending parallel to the cylinder in a plane above the cylinder, said rod extending through the end of said housing opposite to that to which the housing is attached to the frame, said rod being provided with means at its outer end for attachment to a door or the like; and spring means in said housing for yieldably holding said piston and rod in a retracted position, said spring means comprising an elongate member, an outer spring attached to one end of said member and an inner spring attached to the opposite end of said member, the outer ends of said spring means being respectively secured to the housing and to said crosshead.

6. In a door check and return device, an elongated housing adapted to be secured to a door frame or the like at one end and extend in a horizontal position therefrom, said housing having a rod opening at its opposite end; a cylinder in the lower portion of said housing; liquid in said housing covering said cylinder having the upper portion of said housing free of liquid; means providing a restricted fluid passageway from one end of the cylinder, the other end of said cylinder being in open communication with the interior of the housing; a piston in said cylinder; a rod mounted on said piston and extending parallel to and beyond the cylinder in a plane above the cylinder and above the level of the liquid in the housing, said rod extending through the rod opening in the end of said housing out of contact with the sides of said opening, said rod being provided with means at its outer end for attachment to a door or the like; means in said housing for yieldably holding said piston and rod in a retracted position; a combined wiper and baffle in said housing adjacent the end where the rod passes through the housing, said wiper portion being formed of suitable flexible material apertured to receive the rod and said baffle portion being positioned in close proximity to the inner surface of the housing above said cylinder whereby a sudden surge of liquid against said baffle will be prevented from passing the same, said baffle means having a seepage return passage for any liquid which may accumulate between said baffle means and the adjacent end of the housing.
